JOSEPH W. DEARING, OF CHICAGO, ILLINOIS.

GAS-CUT-OFF APPARATUS.

1,264,283.

Specification of Letters Patent. Patented Apr. 30, 1918.

Substitute application for Serial No. 6,899, filed February 8, 1915. This application filed November 29, 1916. Serial No. 134,544.

To all whom it may concern:

Be it known that I, JOSEPH W. DEARING, a citizen of the United States, residing at 3919 Ellis ave., Chicago, in the county 5 of Cook and State of Illinois, have invented certain new and useful Improvements in Gas-Cut-Off Apparatus, of which the following is a specification.

This invention relates to gas cut-offs of 10 that class employed within a building adjacent the meter thereof and adapted for closure through the operation of a pull handle in the vestibule or in the outer wall of the building, and my object is to produce a cut-off apparatus provided with a weight to normally hold the valve of the apparatus open 15 against accidental closure and adapted to lock the valve closed, and which can be closed only through force applied by a manual pull on the handle.

With this object in view, the invention consists in certain novel and peculiar features of construction and combinations of parts as hereinafter described and claimed; 25 and in order that it may be fully understood reference is to be had to the accompanying drawing, in which:—

Figure 1, is a side elevation of a gas cut-off apparatus embodying my invention, certain parts being broken away to disclose features otherwise hidden.

Fig. 2, is a plan view of the same with a part broken away to disclose a connection otherwise hidden.

Fig. 3, is a fragmentary perspective view of a part of a modified form of the weighted lever of the apparatus.

Referring to the drawing in detail, 1 is the body-portion of a standard sliding gate 40 valve, and 2 and 3, are pipes communicating with the valve and leading respectively from the street line to the valve and from the latter to the meter of a building, not shown.

The stem 4, of the valve proper, is provided with an opening or slot 5, for a purpose which hereinafter appears, and 6, is the bonnet of the valve casing, provided with a dome or extension 7, serving as a guide for the upper end of the valve stem. As thus far described, the valve is of standard type, as stated, except that the stem of the ordinary valve extends up through the bonnet and is threaded therein and provided at its upper end with a hand-wheel whereby it 55 may be manually operated. The thread of

the stem and the hand-wheel form no part of this invention and are therefore omitted. The body of the valve is provided in the vertical plane of its longitudinal center, with a communicating tubular offset or extension 60 8, provided at opposite sides with hub portions 9, and 10, the outer end of the latter being preferably diametrically reduced at 11, for a purpose hereinafter explained.

Arranged axially of the hub-portions and 65 extending crosswise through the extension 8, is a suitably journaled shaft, which for convenience of insertion and removal, is composed of a section 12, and a section 13, and mounted on section 12 within the extension 70 and adapted for turning movement therewith, is a lever or crank arm 14, which engages the slot 5 of the valve stem, so that upward and downward movements imparted to said lever or crank arm shall raise the valve 75 from or lower it to its seat.

The outer end of the hub portion 9 of the extension, is closed by the removable cap 15, and through said hub portion, the shaft is adapted to be slipped in or removed from 80 position. A substantially circular yoke 16, is provided at one side with a split sleeve 17, fitting on the reduced end of hub 10, and to clamp said sleeve rigidly in position, it is provided with a pair of superposed lugs 18, 85 through which extends a tap bolt 19.

The sleeve 17, is provided with a series of equi-spaced notches 21, in one edge, any one of which is adapted for engagement with a radial rib or lug 22, projecting from the 90 outer face or end of the hub-portion 10. This interlocked relation between said hub-portion and the sleeve is designed more particularly as a gage for setting the yoke vertically or for setting it horizontally or at an 95 angle of forty-five degrees to the horizontal, accordingly as it is desired to run the pull cable, hereinafter described, in a vertical, horizontal or angular direction.

The yoke is provided opposite the center 100 of its sleeve 17, with a cylindrical portion 23, containing a socket 24, to form a journal for the outer end of section 13 of the shaft, hereinbefore described, and extending through the yoke and mounted rigidly in 105 any suitable manner on the section 13 of the shaft, is a rock-lever 25, which at one end, is of arcuate form and bifurcated at 26, and equipped with a cross-pin 27.

At its opposite end the lever carries a 110

two-part pivoted clamp 28, wherein is secured a pull-cable 29, adapted to extend to the vestibule or other point of the building accessible from the outside thereof. The 5 two-part clamp is preferably made whole by a pair of bolts 30, and to make the connection of the clamp and cable secure, the latter is preferably bent around the bolts in the form of the figure "8" as indicated in 10 dotted lines, Fig. 1. The special method of connecting the cable with the lever is not detailed, as it is unimportant.

The yoke 16, is provided with a depending ear 31, equipped with a pivot pin 32, for a 15 vertically operating lever 33, preferably of substantially U-shape, one arm 34 of the lever being adapted for engagement with the lever 25 at the pull-cord end of the same, for a purpose which is hereinafter described. 20 The other arm of the lever 33, is weighted, preferably by enlarging it as at 35, and it is formed with a curved slot 36, which, when the weight is elevated and the valve is open or elevated, extends concentrically with respect to a point a short distance vertically 25 below the axis of the sectional shaft. When the valve is elevated the pin 27 is at the upper end of said slot, and the inner wall of the latter is pressing outwardly against the 30 pin because of the tendency of the weight to swing downwardly and outwardly with bolt 32 as the axis of motion.

By providing the weighted end of the lever with slot 36, the portion of the lever inward of the slot, constitutes a downwardly-disposed hook terminal 37, the lower end of the same forming a shoulder or stop when the lever is depressed and the valve is closed, to constitute a lock against reverse or 40 opening movement of the valve, as at such time said stop or shoulder lies in the path of upward movement of the pin 27, as indicated by dotted lines in Fig. 1.

With the parts arranged as shown in full 45 lines, Fig. 1, it will be seen that the weighted end of the lever, because of its tendency to swing downward and outward, and the tendency of the pin 27 to swing downward and inward, reliably holds the lever in the position shown, and hence with the valve elevated or open, but that when the cable 29, is pulled upward with sufficient force, the pin is caused to move downward in the slot, it being noted that in this movement, the pin 50 lifts the weighted end of the lever slightly because it applies inward pressure on the hook terminal, due to the fact that the inner edge of the same occupies a plane which intersects that of the downward movement described by the pin. The lifting action, as will be noted by reference to Fig. 1, continues until the pin clears the terminal of the hook and the valve is almost fully 55 closed, it being thus apparent that the valve 60 is closed by the pull applied on the cable.

As the valve is about to be closed by this pull, and the pin clears the lower end of the hook terminal, the weighted lever is released and swings downward, and the lower end of the hook terminal or stop assumes a position in the path of upward movement of said pin, and at about the same time the opposite end or arm of the lever applies a relatively heavy blow upward on the lever 25. The blow applied on lever 25, is 70 transmitted through said lever and connections to the valve so as to seat the same, if possible, more firmly or tightly than it is seated under the pull of the cable. The weighted lever through its pressure on the 75 pull cable lever, tends to maintain the valve in its closed position, and through its hook terminal, renders it impossible for the valve to be reopened except by direct hand manipulation.

It will of course be understood that this cut-off apparatus will be arranged within a locked casing, not shown, because in common and well-known use, and to gain access to the weight and lever, it is necessary to 80 open the casing. To reopen the valve, the operator swings the lever 33 to about the position shown in full lines, Fig. 1, and then swings lever 25, to the position which it occupies in full lines, same figure.

If desired the slot 36, may extend concentric of the axis upon which pin 27 swings, but in this event, the upper end of the slot will be formed with an offset or pocket 36a for the reception of said pin so that downward movement of the latter effected by pulling on the cable 29, shall cause the weighted lever to rise slightly. It will thus be seen that because of the pocket, the weighted lever must be raised slightly before the valve can be seated.

From the above description it will be apparent that I have produced a gas cut-off apparatus embodying the features of advantage enumerated as desirable, and I wish it to be understood that while I have illustrated and described embodiment of the invention, I reserve the right to make all changes properly falling within the spirit and scope of the appended claims.

I claim:

1. A gas cut-off apparatus comprising a valve, a lever connected to open or close the valve, and a weight pivoted to swing from a different center than that upon which the lever swings, and adapted after the lever is operated to close the valve, to automatically operate and apply a blow upon said lever tending to seat the valve more tightly and maintain it in such position.

2. A gas cut-off apparatus comprising a valve, a suitably journaled shaft, an arm rotatable with said shaft for opening or closing the valve, a lever secured on said shaft to operate the same and provided with

a pin, and a weight pivoted at a point spaced from the axis of said lever and provided with a slot engaging said pin, and yieldingly holding the lever through pressure on said pin in the position the lever occupies when the valve is open; said weight when the valve is being closed by said lever, sliding on said pin until the latter is disengaged from the slot and then swinging to 5 a position in the path of reverse movement of said pin to lock said lever against reverse or valve opening movement.

10 3. A gas cut-off apparatus comprising a valve, a suitably journaled shaft, an arm rotatable with said shaft for opening or closing the valve, a lever secured on said shaft to operate the same and provided with a pin, and a weight pivoted at a point spaced from the axis of said lever and provided 15 with a slot engaging said pin, and yieldingly holding said lever through pressure on said pin, in the position the lever occupies when the valve is open; said weight when the valve is being closed by said lever, 20 sliding on said pin until the latter is disengaged from the slot and then swinging to 25 a position in the path of reverse movement of said pin to lock said lever against reverse or valve opening movement.

gaged from the slot and then swinging to a position in the path of reverse movement of said pin to lock said lever against reverse or valve-opening movement, and applying a blow upon said lever to seat the valve more 30 tightly.

4. A gas cut-off apparatus comprising a valve, a lever connected for opening and closing the valve, and a pivoted weight adapted when at one point in its pivotal 35 movement, to engage said lever and thereby hold the valve yieldingly open, and when at another point in its pivotal movement, to engage said lever and thereby lock the valve against opening movement; said weight 40 having an arm for striking said lever after the closing movement of the latter is ended, to apply force tending to seat the valve more firmly.

In testimony whereof I affix my signature 45 in presence of two witnesses.

JOSEPH W. DEARING.
